UNITED STATES PATENT OFFICE.

GEORGE A. SWEET, OF ASHTABULA, OHIO.

GRINDING DEVICE.

1,199,836.

Patented Oct. 3, 1916.

Application filed March 28, 1916. Serial No. 87,320.

To all whom it may concern:

Be it known that I, GEORGE A. SWEET, a citizen of the United States, residing at Ashtabula, in the county of Ashtabula and State of Ohio, have invented new and useful Improvements in Grinding Devices, of which the following is a specification.

This invention contemplates the provision of a grinding device especially intended for use in connection with a leather splitting machine, although susceptible for use in other connections.

In machines of the above mentioned character the cutting blade is in the nature of a continuous band trained over pulleys to travel at a considerably high rate of speed, in view of which fact the blade must be reasonably soft to make the turns. The present method of sharpening these bands results in passing the bands between a pair of rapidly revolving grinding wheels, which provides the band with a rough and tender edge, that does more or less damage and inferior work. With the band in this condition the cutting edge is often turned over by the shot or thorns frequently found in hides, thereby rendering the hide beyond repair. Considerable time is also spent in grinding the breaks out of the band, with a resultant waste of the latter.

It is therefore the purpose of my invention to provide a grinding device embodying among other features, a pair of revolving grinding elements which are arranged to lie flat against the upper and lower sides respectively of the cutting edge of the band or blade to provide a smooth beveled edge, the grinding elements being capable of adjustment to different angles or inclinations to accommodate themselves to the bevel of the blade, thereby making the cutting edge both keen and tough, which splits the leather clean and smooth, and in a more uniform degree.

Another important characteristic of the invention resides in the provision of a yieldable means for holding the grinding elements in contact with the blade under any desired degree of pressure, the yieldable means functioning to absorb the thrust with a view of allowing the grinding elements to revolve freely, the latter being actuated by the band passing between the same.

The nature and advantages of the invention will be better understood when the following description is read in connection

with the accompanying drawings, the invention residing in the construction, combination and arrangement of parts as claimed.

In the drawings forming part of this specification like numerals of reference indicate similar parts in the several views and wherein:

Figure 1 is a fragmentary side elevation of the leather splitting machine, illustrated to show the manner of associating the grinding device therewith. Fig. 2 is a side elevation of one of the grinding devices as a unit. Fig. 3 is a side elevation of the invention showing the different grinding devices arranged at an angle with respect to each other. Fig. 4 is a sectional view taken on line 4-4 of Fig. 3 looking in the direction of the arrow. Fig. 5 is a sectional view taken on line 5-5 of Fig. 4.

The use of the invention in connection with a leather splitting machine is sufficiently characteristic of its utility and admirably illustrates the invention, and will constitute one of its most useful applications. For this reason the description is addressed to the coöperation of the invention with a leather splitting machine, but it is to be understood however, that the device is susceptible for use in other connections, and that such general application is contemplated by the claims.

Referring more particularly to the drawings in detail 10 indicates generally a leather splitting machine of any suitable construction, embodying of course the cutting blade 11 which consists of an endless band trained over the pulleys 12. Machines of this character are generally provided with grinding elements 13 arranged in the manner shown in Fig. 1, and which elements grind the blade very fast with a resultant rough and tender edge which does inferior work. These grinding devices are to be replaced by the device forming the subject matter of my invention.

In the present instance the invention embodies a base 14 adapted to be secured to the floor in any suitable manner, and from which rises a standard 15 supporting at its upper end an iron strap 16 adapted to extend across the bed plates of the machine. The standard 15 supports two units or grinding devices which are identical in construction, and a brief description of one will suffice for both.

Secured to the standard 15 is a bracket 17

which may be of any suitable construction for sliding adjustment upon the standard, and provided with means for holding the bracket fixed relatively to the standard in any desired position, which in this particular instance consists of a threaded bolt 18 passing through the separated ends of the clamp. Projecting centrally from the bracket 17, and at right angles from the support 15, is an arm 19 which supports a bracket 20 of a construction similar to the bracket 17, the bracket being mounted to turn upon the arm 19 for the purpose to be hereinafter described, and provided with a bolt 21 passed through the separated ends of the bracket and through the instrumentality of which the bracket is held in fixed position on the arm 19.

Projecting from one side of the bracket 19 is a threaded stud 23 adapted to pass through a suitable opening in the vertical limb 24 of a substantially U-shaped member as shown, and threaded upon the stud 23 is a nut 25 for holding these parts operationally associated. The extremities of the parallel limbs 26 of said U-shaped member are forked to receive the opposite ends of a vertical shaft 27 upon which the grinding wheel 28 is journaled, the shaft 27 having associated therewith nuts 29 arranged at the opposite sides of the limbs 26 for holding the shaft and U-shaped member fixed relatively.

It might here be stated that one of the grinding devices as a unit projects from one side of the standard 15 while the other grinding device extends from the opposite side of the standard, and is reversely disposed with respect to the first mentioned unit. This specific disposition of parts is essential in carrying into effect the idea of having the grinding wheels 28 of the different units arranged to lie flat against respectively the upper and lower sides of the cutting blade to provide a smooth beveled cutting edge therefor. By reason of the manner in which the units are supported upon the standard 15, it will be manifest that the units may be adjusted vertically upon the standard, or rocked upon the arms 19 of the brackets 17 to assume different angular or inclined positions to allow the grinding wheels 28 to accommodate themselves to the bevel of the blade, so as to produce both a keen and tough cutting edge which not only splits the leather clean and smooth, but also makes a more uniform and even piece of work.

With a view of holding the grinding wheels 28 against the cutting blade with any desired degree of pressure, I preferably make use of a coil spring 30 which encircles the shaft 27, having one end bearing against a collar 31 and its opposite end bearing against a ball bearing associated with the

steel bushing 32 mounted on the shaft and passing through the wheel 28. The collar 31 is slidably adjustable upon the shaft 27, for the purpose of regulating the tension of the spring 30, the collar carrying a set screw 33 for engagement with the shaft whereby the collar may be held fixed relatively thereto in any of its adjusted positions. It is to be borne in mind that the grinding wheels 28 by reason of their disposition with respect to the cutting blade 11 are operated by the friction between the parts as the blade passes between the wheels. In consideration of this fact it is to be noted that the springs 30 in addition to holding the grinding wheels under pressure against the cutting blade, also function to absorb the thrust imparted to the wheels 28 during the operation of the device, and in consequence permit the wheels to revolve freely consistent with the requisite degree of pressure thereon to provide a keen and smooth cutting edge for the blade.

Depending from the iron strap 16 adjacent one end thereof is a bolt or the like indicated at 35 which is secured in any suitable manner. The lower end of the bolt supports a pair of spaced plates 36 each having secured to the inner face thereof a piece of felt or other suitable material 37 for wiping the blade. The bolt 35 is disposed in parallelism with the standard 15 which positions the plates 36 at one side of the grinding devices, it being manifest that the blade is adapted to pass between the pieces of felt 37 which not only wipe the blade but tend to steady the same.

It is believed that from the foregoing description the nature and advantages of the invention will be readily apparent, it being understood that the device is in the nature of an attachment which can be secured to the machine in quick order without altering or changing the mechanism of the machine. It is to be further understood that I do not limit myself to the precise construction shown as the same is merely illustrative of one embodiment of the invention, and that such changes may be resorted to when desired as fall within the scope of what is claimed.

What is claimed is:—

1. In a grinding device, the combination with a running blade, of a vertical standard, a pair of revolving grinding elements supported from said standard and capable of vertical adjustment thereon, means for holding said elements in adjusted position to engage the upper and lower sides respectively of the blade, means for exerting pressure on said elements, and means for regulating the pressure exerted by said last mentioned means.

2. In a grinding device, the combination with a running blade, of a vertical standard,

- a pair of grinding elements slidably supported on said standard, and also mounted for vertical swinging movement, said elements being arranged to engage respectively 5 the upper and lower sides of the blade, means for holding said elements in different inclined positions with respect to the blade, means for exerting pressure on said elements, and means for regulating the pressure exerted by said last mentioned means.
3. In a grinding device, the combination with a running blade, of a vertical standard, a pair of revolving grinding elements mounted on said standard for vertical 15 swinging movement, said elements being arranged to engage respectively the upper and lower sides of the blade, means for exerting pressure on said elements, and means for regulating the pressure exerted by said last 20 mentioned means, and a combined guide and wiper for said blade secured to said standard and disposed at one side of said elements.
4. In a grinding device, the combination with a running blade, of a vertical standard, clamps secured thereto and having arms projecting laterally from the opposite sides thereof, a grinding device mounted on each of said arms, and including a bracket supported for vertical swinging movement, a 25 revolving grinding element supported on
- said bracket, and said elements being arranged to engage respectively the upper and lower sides of the blade, means for holding the brackets in adjusted position, means for exerting pressure on said elements, and means for regulating the pressure exerted by said last mentioned means.
5. In a grinding device, the combination with a running blade, of a vertical standard, 40 clamps adjustably mounted thereon, arms projecting laterally from said clamps and disposed at the opposite sides of the standard, a grinding device for each clamp, including a substantially U-shaped bracket 45 swingingly mounted on said arm of the clamp, a shaft supported by said bracket, a revolving grinding element carried by the shaft, said elements being arranged to engage respectively the upper and lower sides of the blade, means for holding said brackets in adjusted position, a spring encircling the shaft of each grinding device for exerting pressure against its grinding element, and means for regulating the tension of said spring.

In testimony whereof I affix my signature in presence of two witnesses.

GEORGE A. SWEET.
